RADIUS BAR

Edwin A. Walcher, Calumet City, and Walter H. Baselt, Chicago, Ill., assignors to American Steel Foundries, Chicago, Ill., a corporation of New Jersey

Application July 15, 1935, Serial No. 31,460

5 Claims. (Cl. 188—219)

This invention relates to a new and improved radius bar or horizontal equalizer for railway car brakes and more particularly to such a bar formed as an integral truss structure.

5 The radius bar or equalizer for railway car brakes is usually mounted on the truck and serves to connect the car body pull rod with the brake levers carried by the truck. Due to relative movement between the car body and truck, the connection between the body pull rod and radius bar is a rolling or sliding one, the contact usually being upon a circular arc. Also, there is a twisting action on the radius bar due to the relative change of position of the truck and car body because of spring deflection, swiveling, and the like movements.

Radius bars have heretofore been constructed as built up members comprising a plurality of parts riveted together or as a unitary solid bar. 20 The built up radius bars have in general consisted of two main members held together by additional members, all of which parts must be carefully made and accurately assembled. Such a construction is expensive to make and, due to the fabricated construction, requires a greater weight of metal for a given strength than a unitary construction. On the other hand, a truss construction is very desirable as making the 25 most efficient use of a given weight of metal, in this respect being superior to a solid metal bar.

It is therefore one of the objects of this invention to incorporate in a radius bar the advantages of the truss type of construction while avoiding the disadvantages which have heretofore been present in radius bars of such form.

It is a further object to provide a bar of this character which is formed integrally as a unitary member with openings formed therein.

It is also an object to provide a unitary truss construction comprising integral tension and compression members and struts.

It is an additional object to provide a truss construction in which the members and struts form a window opening for the application of 45 brake actuating mechanism.

It is another object to provide a construction which is simple in design and in installation and operation, and adapted for commercial production and use.

50 With these and various other objects in view, the invention may consist of certain novel features of construction and operation as will be more fully described and particularly pointed out in the specification, drawings and claims appended hereto.

In the drawings, which illustrate embodiments of the device, and wherein like reference characters are used to designate like parts—

Figure 1 is a plan view of the radius rod;

Figure 2 is a side elevation;

Figure 3 is a view as seen from the right end 5 of Figure 1;

Figure 4 is a fragmentary top plan view of one end of a truck construction showing the application thereto of the radius bar embodying the invention;

Figure 5 is a fragmentary end elevation of the truck construction and radius bar application 10 illustrated in Figure 4;

Figure 6 is an enlarged fragmentary top plan view of the radius bar and associated operating 15 mechanism embodying the invention;

Figure 7 is a fragmentary sectional elevation taken substantially in the plane indicated by the line 7—7 of Figure 6;

Figure 8 is an enlarged fragmentary top plan 20 view corresponding to Figure 6 showing a different form of operating means;

Figure 9 is a fragmentary sectional side elevation through a portion of a truck construction, 25 brake operating mechanism and the associated car body showing the normal relative positions between the operating rod and the radius bar;

Figure 10 is a fragmentary sectional side elevation corresponding to Figure 9 showing the position of the brake mechanism and radius bar when the car body is in a lowered position as a result of the springs being compressed under load;

Figure 11 is a fragmentary sectional side elevation corresponding to Figure 9 showing the position of the brake mechanism and radius bar when the car body is in an abnormally high position 35 such as it might assume when the springs were expanded to a maximum, as may sometimes occur under service conditions.

This application is a continuation-in-part of 40 application Serial No. 668,316, filed April 28, 1933.

Referring first of all more particularly to the unitary radius bar 10, such as illustrated in 45 Figures 1, 2 and 3, said bar includes a tension member 11 and compression member 12 joined into the integral reduced end portions 13 which carry the trunnions 14. The trunnions 14 carry the castellated nuts 15 to retain the brake lever and radius bar connections in place. The radius bar is also provided with hinge brackets 16 which are riveted to the bar, and serve to connect the bar to supporting links.

The truss construction of the radius bar is 55

completed by the integral struts 20 which connect intermediate portions of the tension and compression members 11 and 12 respectively, and the struts are so spaced as to form a window 5 opening for the application of the brake actuating mechanism.

The radius bar is provided with wear plates 17 and 18, and wear plate 17 has a vertically extending portion 19 which covers the inner face of 10 the tension member 11 and serves as a contact surface or track for the roller carried by the body pull rod jaw, while each of the wear plates serves as a wear member for the operating means such as the jaws of the rod 64 formed by the straps, 15 all as later described.

In forming the radius bar, it is preferably cut out of a single piece of steel with the trunnions formed on the ends in an upsetting machine. Due to the one piece construction it is 20 less apt to give trouble in service than the built up design.

Referring now more particularly to Figures 4 and 5, the truck 22 includes the side frame 24 and the end connecting members 26 secured to 25 said side frame. Suitable brakes may be applied to each side of each of the wheels 29. In the construction shown, the brake rigging is similar to that illustrated and particularly described in 30 Baselt Patent No. 2,002,930, granted May 28, 1930. On each side of the wheels suitable brake levers are provided, having brake shoes, and connected by the spaced pull rods 27, the end brake lever 28 being a dead lever and pivotally connected to the bracket 30 provided on the end rail 26, the 35 brake lever being provided with the pivotally mounted head 32 intermediate the ends thereof. The inner brake lever 34 is a live brake lever, being supported by means of the brake hangers 36 pivoted as at 38 to the side frame. The live 40 brake lever is also provided with a suitable brake shoe and the upper end of said lever is pivotally connected through the clevis 40 to the live horizontal lever 42, the outer end of said live lever being pivotally connected as at 44 to the pull 45 rod 46 connected to a similar horizontal lever associated with the adjacent wheel.

The pull rod 48 is pivotally connected as at 50 to the horizontal lever 42 intermediate the ends thereof, the other end of said pull rod being 55 connected as at 52 to the trunnion 14 of the radius bar 10, and being fastened thereto by means of the nut 15. The release spring 54 is mounted on the bar 56 slidably mounted in the bracket 58 provided on the side frame, the other 60 end of said bar being connected through the bracket 60 to the pull rod 48, the spring being confined between the bracket 58 and the retainer 62 provided on said bar. Hand or other operating means may be provided for operating the 65 brake rigging through the radius bar. In this case the operating means directly connected to said bar may take the form of the rod 64, the end thereof being formed with the jaw 66 embracing the radius bar, said jaw between the tension and compression members being provided with the roller 68 adapted to have rolling contact with the 70 arcuate wear member 19 whereby the brakes may be equalized regardless of the angularity between the operating means and the truck or radius bar.

The support for the radius bar on the truck is provided by means of the supporting levers 70 pivotally mounted as at 72 to suitable brackets 74 provided on the end member 26. The upper ends 75 of said supports are pivotally mounted as at 76

to the bracket 16 provided on the radius bars in substantial alignment with the struts 20 thereof.

In order to more adequately illustrate the relative positions of the parts of the operating means and the radius bar, a reference may be had to Figures 6 and 7. The operating rod or body pull rod 64 provided with the jaws 66 is disposed so that the jaws embrace the tension and compression members 11 and 12 of the radius bar. The roller 68 is pivotally connected as at 10 78 to the upper and lower jaws 80 and 82 so that the roller is disposed between the tension and compression members and has a rolling contact with the vertically extending leg 19 of the member 17, said member being connected as by the 15 rivets 84 to the tension member 11.

The upper jaw 80 is provided with the rubbing strip and reenforcing member 86 adapted to have sliding contact with the top of the tension member 11 when the parts are in normal position, 20 that is, when the car body is light or substantially without load. The lower jaw 82 is provided with the reenforcing or rubber strip 88 secured thereto as by means of the rivets 90 and adapted to have sliding contact with the member 18 secured on 25 the under side of the compression member 12.

The end of the operating rod 64, in the construction shown in Figures 6 and 7, is pivotally connected as at 92 to the dead operating lever 94 pivotally connected as at 96 to the car body, 30 said lever being adapted to be operated by the rod 98 operated either by a cylinder or hand operating means.

In the construction illustrated in Figure 8, the operating rod 164 is similar to the operating rod 35 64, the end removed from the radius bar being shown as provided with the flexible connection 100 for operation by a brake staff or other operating means.

In order to show certain of the functions of the 40 reenforcing or wear plates 17 and 18, a reference may be had to Figures 9, 10 and 11, as well as Figures 7 and 8. The truck frame 102 is shown as provided with the depending pedestals 104 adapted to accommodate journal means (not 45 shown) having cooperative engagement with the axles 106 of the wheel and axle assemblies 108. Brakes such as shown and described in Figures 4 and 5 may be used. The truck frame is provided with the end member 110 to which the 50 brake 74 is secured, as has already been described with respect to Figures 4 and 5.

The radius bar 11 and the associated operating rod 64 are shown, the operating lever 94 being pivoted as at 92 to the jaw 112 of the rod 64. A 55 support 114 is provided on the car body 116 for slidably supporting the dead lever 94 and its associated mechanism. It will thus be seen that when there is no relative change of position between the car body 116 and the truck frame 102, 60 the wear plate 86 rests upon the tension member 11.

In operation, it has been found advisable and necessary to provide a wear plate 17 on the bottom of tension member 11, said wear plate being 65 provided with the upwardly extending leg 19 adapted to form a track for the roller 68. The wear plate 18 is provided on the under side of the compression member 12 and adapted to have sliding contact with the wear member 88 70 provided on the lower jaw 82.

The wear member is provided both on the compression member and on the jaw due to the extreme conditions of operation when tipping of the radius bar occurs. When the car body moves 75

downwardly under load as viewed in Figure 10, the wear plates 18 and 88 come into contact and the wear member 17 is contacted by the lower jaw 82 so that when angling occurs the wear is taken through the wear members, and the lower jaw of the operating rod 64. The same operation between the wear plates 18 and 88, and the lower jaw of the wear member 17 occurs when there is upward movement at the right side of the car as viewed in Figure 11. It is understood that under some conditions of operation the jaw of the rod 64 may contact the radius bar in other than the described positions which are, however, illustrations of the most usual conditions which determine the position of the wearing and reenforcing members. Thus, not only do the wear plates prevent wear of the radius bar, but they also perform the function of stiffening the radius bar, and the member 19 also forms a track for the operating roller. It is comparatively easy to replace the operating rod 64 or the wear plates, and this may be done comparatively inexpensively, and a stronger and lighter bar can also be provided.

25 Thus, with the construction shown, the wear members perform a plurality of functions which obviate the necessity of replacing the radius bar.

It is to be understood that we do not wish to be limited by the exact embodiments of the device shown, which are merely by way of illustration and not limitation, as various and other forms of the device will of course be apparent to those skilled in the art without departing from the spirit of the invention or the scope of the claims.

What is claimed is—

1. In a brake arrangement, the combination of brake rigging, a radius bar connected to said rigging, said bar being substantially of truss construction including tension and compression members merging adjacent the ends thereof and having a window therebetween, said tension member having a wear member on the lower side thereof and extending into said window to form a track therein, a wear plate on the lower side of said compression member, and a pull rod for moving said radius bar to operate said rigging, said rod having a bifurcated jaw receiving said radius bar, said jaw including upper and lower members connected by a member disposed in said window and adapted to engage and slide on said track, a wear plate on said upper member over said tension member, and a wear plate on said lower member below said compression member.
2. In a brake arrangement, the combination of brake rigging, a radius bar connected to said rigging, said bar being substantially of truss construction including tension and compression members merging adjacent the ends thereof and having a window therebetween, said tension mem-

ber having a wear member on the lower side thereof and extending into said window to form a track therein, a wear plate on the lower side of said compression member, and a pull rod for moving said radius bar to operate said rigging, said rod having a bifurcated jaw receiving said radius bar, said jaw including upper and lower members connected by a member disposed in said window and adapted to engage and slide on said track.

3. In a brake arrangement, the combination of brake rigging, a radius bar connected to said rigging, said bar being substantially of truss construction including tension and compression members merging adjacent the ends thereof and having a window therebetween, said tension member having a wear member on one side thereof and extending into said window to form a track therein, a wear plate on the lower side of said compression member, and a pull rod for moving said radius bar to operate said rigging, said rod having a bifurcated jaw receiving said radius bar, said jaw including upper and lower members connected by a member disposed in said window and adapted to engage and slide on said track.

4. In a brake arrangement, the combination of brake rigging, a radius bar connected to said rigging, said bar being substantially of truss construction including tension and compression members merging adjacent the ends thereof and having a window therebetween, said tension member having a wear member on one side thereof and extending into said window to form a track therein, a wear plate on one side of said compression member, and a pull rod for moving said radius bar to operate said rigging, said rod having a bifurcated jaw receiving said radius bar, said jaw including upper and lower members connected by a member disposed in said window and adapted to engage and slide on said track.

5. In a brake arrangement, the combination of brake rigging, a radius bar connected to said rigging, said bar being substantially of truss construction including tension and compression members merging adjacent the ends thereof and having a window therebetween, said tension member having a wear member on one side thereof and extending into said window to form a track therein, a wear plate on the same side of said compression member, and a pull rod for moving said radius bar to operate said rigging, said rod having a bifurcated jaw receiving said radius bar, said jaw including upper and lower members connected by a member disposed in said window and adapted to engage and slide on said track.
